FRITZ KILLING, OF COLOGNE, GERMANY

MEANS FOR FACILITATING THE TYING AND SEALING OF PACKAGES

Application filed November 4, 1927, Serial No. 231,126, and in Germany November 13, 1926.

In contradistinction to the most usual manner of tying packets intended for exportation which are tied up so that they cannot be untied without much difficulty, certain packets 5 are sealed with the express purpose of facilitating as much as possible the untying thereof with little trouble and without injuring the binding cord. Thus, a seal for the binding cord or string of a package comprises a 10 double headed bobbin consisting of two sheet metal or cardboard discs connected by a short hollow stem in which the beginning of the cord or the like is secured. The part of the cord lying at the right angular turning point 15 at the crossing between the first and second bindings, and also particularly the free end of the cord are wound round the outside of the hollow stem between the two discs several times, and are so retained in the narrow space 20 between them by a clamping action that the clamping action is released by twisting back the free end of the cord. In order to produce a sheet metal cord seal which is suitable for exportation and from which it is ex- 25 tremely difficult to release the cord without destroying the closing means, the use of closing means has already been proposed consisting of two sheet metal caps to be united, which partly serve the purpose of supporting 30 means in the tying operation itself in addition to serving as the turning point of the cord. The two disc or head-shaped parts of this sheet metal seal are only united, how- 35 ever, at their outer edges by means of nippers after the knot is tied, as is usual when a pack- 40 age is wrapped with cord and the closure ef- fected by a knot.

According to the present invention the seal utilized in tying packages comprises a bob- 45 bin consisting of two end discs connected by a central hollow stem, said bobbin being used in the manner referred to for supporting and stretching the tying means at the point of crossing of the first and second strands and for providing a releasable clamping connec- 50 tion for the free end of the cord by simply twisting it around the stem. The bobbin, however, as distinguished from the above-mentioned releasable seal is so formed that when the central hollow rivet is compressed

by means of a punch similar to an eyelet hole punch to imprison the simple loop, formed by the turns around the stem and end of the cord, between the two discs a capsule connection is formed which is practically 55 impossible to break. In itself, however, the use of bobbin-shaped closures for imprisoning a binding member around a central compressible hollow rivet has already been proposed. In such previous closures, however, 60 it is purely a matter of a simple closing plug in the proper sense in which a simple short wire limb serves as the binding member which when fastened between the outer edges of the two sheet metal bobbins produces the disadvantage that the closure can be undone as in 65 the package seal first mentioned by applying an appropriate twisting force and can be remade unperceived.

Apart from the fact that the latter dis- 70 advantage is obviated by the seal forming the subject of the present invention by forming notches in one of the two discs of the bobbin in which the parts of the binding medium 75 passing therefrom are immovably held, the present invention is concerned with the common use of means serving to facilitate tying up and securing of the binding closure, whilst the bobbin facilitating the unitary tying up 80 operation is finally converted into a sheet metal plug seal.

Particular advantages accompany the pro- 85 duction of the tied connection in that all bothersome and lengthy operations of tying knots, such as was formerly necessary in tying a package with cord, are completely avoided. The work and utilization of time necessary in tying a package is not only very consider- 90 ably reduced, but also the security of the seal is much enhanced.

In the accompanying drawings,

Fig. 1 is a side view of the bobbin formed according to the invention,

Fig. 2 is a plan view corresponding there- 95 to,

Fig. 3 is a sectional view on the line III—III, Fig. 1,

Fig. 4 is a perspective view showing the manner of securing the beginning of the cord 100 in the bobbin,

Fig. 5 is a perspective view illustrating the closing operation in the production of the first turn of a package tie according to the invention,

5 Fig. 6 shows in a similar manner the twisting operation in the final stage in the tying operation,

10 Fig. 7 is a perspective view showing how the seal is made by utilizing an eyelet or like punch,

15 Fig. 8 is an under plan view of the seal when made, and

Fig. 9 is an enlarged cross sectional elevation on the line IX-IX, Fig. 8.

20 15 The bobbin adapted for use in the tying operation and at the same time forming the plug of the ultimate seal consists of a sheet metal body composed for example of two parts. The end disc or upper plate 1 of this 25 bobbin constituting the outer one in use has a smooth, annular, inturned curved edge 2 and also a central hollow stem or rivet 3 on the outer reduced end of which, advantageously of coniform shape, the lower part 4 30 constituting the other end plate is applied. This lower part 4 has a central depressed portion 5 forming a conical sleeve engaging the stem 3 and having an inturned annular flange or lip. The inner end of the hollow rivet 3 35 has an outwardly turned flange 6 so that the parts 3 and 5 cannot be separated from one another. The edge of the lower part is advantageously provided with four cut-out portions or notches 7 and the tongues 8 formed 40 between these are bent towards the upper plate at a steep angle.

45 In the tying operation the beginning of the cord is first of all formed into a simple loop knot 10, as is shown in Fig. 1, and is drawn 50 tight around the hollow rivet of the bobbin without any further knotting being necessary. After the cord has been drawn around the package 11 in the usual manner, the end 13 of the first turn is so laid between the two end 55 plates of the bobbin that the upper plate of the latter is on the outside. Thus without further trouble the two ends 12, 13 of the cord formed by the first turn around the package proceed from and lie under two diametrically 60 opposed notches 7 in the lower part 4 of the bobbin and so are maintained in correct position. After the cord has been turned at right angles to the first turn it can be drawn tighter or made slack as desired. Thus the bend in 65 the cord between the end part 13 of the first turn and the beginning of the second turn is so laid over the loop 10 that not only is accidental untying of the loop prevented but relief of the tension applied to the first turn 70 is also prevented.

75 After the cord is pulled around the package to form the second turn, the end part is again placed sideways between the two end plates 80 and after preliminary tensioning the free end is wound around one or more times between

the plates, as shown at 16, Fig. 9. The uppermost winding is clamped into frictional contact between the previous windings with sufficient force to ensure that they cannot loosen by themselves and the tension applied to the 70 second turn of the cord around the package cannot be relieved. In order to ensure that the seal thus made shall not be broken or undone as could easily be done at the present stage, and in order to ensure against unperceived release thereof a punch similar to an eyelet hole punch is utilized to effectually seal the package. As shown in Figure 7 a punch of known kind is placed with its lower supporting matrix under the lower part 4 of the 75 bobbin and with its co-operating upper piston over the upper plate 1. When the punch is operated in known manner the two plates are forced together and the rivet is more or less collapsed thus causing the inturned flange 80 6 to roll up and the ends of the tongues 8 to spring in behind the curved channel 2 and be firmly held there as indicated in Figure 9. By forcefully squeezing together the various 85 coiled parts of the cord within the bobbin as can be attained with facility and complete reliability by compressing the parts of the bobbin by a punch, the two ends of the cord are much more firmly and reliably sealed and the seal is practically completely unbreakable 90 95 without leaving visible evidence that it has been tampered with. Also as shown in Figure 9, the collapsing of the rivet causes the upsetting of its flanged end so that it will be bound within and against the conical sleeve 5 in such 100 manner as to lock the two members of the seal internally, in addition to the external locking connection between the tongues 8 and channel 2.

105 Instead of forming the rivet in one piece with the upper plate 1 it can be formed in one piece with the lower part 4 provided with the notches. Also the central rivet can be an independent unit in which the two end plates are so applied and held by suitably swelling 110 the ends that they can only slide inwards.

I claim:—

115 1. A package seal comprising a pair of clamping disks, and a collapsible hollow stem connecting said disks, one of the disks being provided with an inwardly directed marginal retaining flange forming a locking channel, and the other locking disk having an annular series of spaced tongues forming intervening cord passages, said tongues being normally directed toward the first-named disk and the free edges thereof being adapted, upon the collapse of the collapsible stem, to be moved radially outward and interlocked 120 with said locking channel.

125 2. A package seal comprising a pair of clamping disks, and a collapsible stem connecting and normally holding said disks in spaced relationship so that portions of a tying cord may be passed about the stem,

one of said disks being provided with an annular series of spaced tongues forming passages for the cord portions and adapted to be closed by engagement of the free edges of the tongues with the other disk when the collapsible stem is collapsed.

3. A package seal comprising a pair of clamping disks, one of said disks having a locking channel, a collapsible stem connecting said disks and normally holding them in spaced relationship so that portions of a cross-tie cord may be passed about the stem, and the other disk being provided with two pairs of tongues arranged at an angle to each other and forming cord receiving passages between them, said tongues being normally bent downwardly and outwardly at an angle toward the first-named disks and their free edges being adapted for radial outward movement and interlocking engagement with the locking channel of the first-named disk when the stem is collapsed.

4. A package seal comprising a pair of spaced clamping disks, one of said disks having an inwardly projecting retaining sleeve, and the other of said disks having an inwardly projecting collapsible stem projecting into said sleeve and the free end of which is adapted to be collapsed therein, one of the disks being provided with an annular series of spaced tongues forming cord receiving grooves normally open at their inner ends and adapted to be closed by the first-named disk upon the collapse of the collapsible stem.

35 5. A package seal comprising a pair of spaced clamping disks, one of said disks having an inwardly projecting retaining sleeve and the other of said disks having an inwardly projecting collapsible stem fitting within said sleeve and the free end of which is adapted to be collapsed therein on the closure of the seal, one of the disks being provided with a marginal retaining flange, and the other disk being provided with an annular series of tongues forming receiving passages open at their inner ends and adapted to be closed by the other disk when the stem is collapsed, said tongues being bent at a downward and outward angle toward the channel disk and the free edges thereof being adapted to be moved radially outward and interlocked with the channel on the closure of the seal.

6. A package seal comprising a pair of spaced clamping disks, one having an in-turned marginal retaining channel, and the other having an annular series of spaced lapping tongues forming intervening cord receiving passages normally open and adapted to be closed by the channel disk on the closure of the seal, and a collapsible stem connecting the disks, said tongues being normally bent outward and downward at an angle for radial downward movement to engage the channel disk and to be forced into the chan-

nel for interlocking engagement therewith when the stem is collapsed.

7. A package seal comprising a pair of clamping disks, one of said disks having an inwardly projecting conical retaining sleeve, and the other of said disks having an inwardly projecting conical collapsible stem fitted within said sleeve, the free edges of the sleeve and stem being provided with stop flanges, and said stem being adapted to be collapsed within the sleeve, one of the disks being provided with a marginal retaining flange, and the other disk having an annular series of tongues forming cord passages normally open at their outer ends and adapted to be closed by the channel disk when the stem is collapsed, said tongues being bent downwardly and outwardly at an angle toward the channel disk and their free edges being adapted for contact therewith and for outward movement into interlocking engagement with the channel of the channel disk when the stem is collapsed.

In witness whereof I affix my signature.
